EVERETT A. JOHNSON, OF PARK RIDGE, ILLINOIS, ASSIGNOR TO STANDARD OIL COMPANY, OF CHICAGO, ILLINOIS, A CORPORATION OF INDIANA

DRY CLEANING DEVICE

Application filed April 30, 1932. Serial No. 608,427.

My invention relates to a new and improved type of home dry cleaning device particularly suited to the rapid and economical dry cleaning of small garments and other textile fabrics. It is particularly characterized by certain new features which are adapted to permit rapid and inexpensive dry cleaning, the removal of the fluid from the fabrics after dry cleaning, and filtration of the dirty fluid. One object of my invention is to produce a device which will permit the use of two ordinary open-mouthed containers as a dry cleaning system and as a recovery system for dry cleaning fluids. Another object of my invention is to produce a new and improved home dry cleaning machine. Further objects will become apparent as the description of the invention proceeds.

My invention may be more particularly described by reference to the accompanying drawing in which:

Figure 1 represents a sectional elevation of the main portion of the device;

Figure 2 represents a sectional plan view along the line 2—2 of Figure 1; and

Figure 3 represents an elevation of the device, including the containers, at one stage in its operation as a dry cleaning system.

Referring to the drawing in detail, a screw thread 11, preferably constructed of sheet metal, is adapted to receive corresponding screw threads located on the mouth of an open-mouthed container 12. A generally similar but oppositely disposed screw thread 13 is adapted to receive a corresponding screw thread on the mouth of an open-mouthed container 14. Screw thread 11 is integrally attached to a member 15 and screw thread 13 is integrally attached to a member 16. Members 15 and 16 are also integrally attached to each other in such manner as to form a partial partition disposed between screw threads 11 and screw threads

13. It will be understood that it is possible to construct the device in such manner that members 15 and 16 will be replaced by a single member attached to both screw threads 11 and 13. In any event, members 15 and 16, or a corresponding similar mem-

ber, are perforated as shown at 17 so as to permit the free passage of liquid but not to permit the free passage of fabrics being cleaned. It will be understood that this perforated member may be replaced by a wide 55 meshed screen or other type of foraminous partition.

In a preferred embodiment the device illustrated in Figures 1 and 2 is used as the cover of the container 12, used for the 60 handling and distribution of dry cleaning fluid. In this case it is, of course, necessary to use a discoid, impervious and fluid-tight gasket located in the position shown for an-

annual gasket 18 in order to prevent the loss 65 of fluid through perforations 17. In operating the system as a dry cleaning device the fabrics to be cleaned are inserted in container 12 and the cover, together with the gasket is replaced, whereupon container 70

12 is shaken or otherwise agitated to give efficient dry cleaning. It is preferable, however, that the cleaning operation be conducted, using two containers. In order to

accomplish this, annular gasket 18, which 75 will permit the free passage of fluid through perforations 17, is used in place of the discoid gasket previously mentioned. The

fabrics to be cleaned are inserted in container 12, screw threads 11 are positioned on 80 the corresponding screw threads of container 12, and container 14 is placed in position by screwing into screw thread 13. It is desirable to use a washer or gasket 19 in order to obtain fluid-tight connection be- 85

tween container 14 and screw threads 13. When the two containers have been put in place the whole system may be agitated by shaking or otherwise, and the fluid will pass freely back and forth from container 12 90 to container 14 while the fabrics being cleaned are retained in container 12. This insures a more thorough cleansing action, since the cleaning fluid does not travel with the fabrics but is repeatedly washed back 95

and forth through them. After the cleaning has been accomplished, the device is placed in position, as shown in Figure 3, with container 14 lowermost and container 12, in which the fabrics are confined, in 100

inverted position. By allowing the system to stand in this position the fluid will drain out of the fabrics through perforations 17 into container 14.

5 The device of my invention has a still further advantage in that it can be used to reclaim the dirty dry-cleaning fluid after the cleaning operation. This can be done by removing container 12, taking out the 10 fabrics, unscrewing the screw threads 13, and placing a felt pad, filter paper or other filtering disc 20 in position against member 16 as shown in dotted form in Figure 1. Screw threads 13 are then repositioned on 15 container 14 in such manner as to hold filtering disc 20 in position. Container 12 is then replaced in screw threads 11 and the whole device is then inverted so that container 12 is lowermost. The fluid will then 20 filter through filtering disc 20, leaving suspended dirt behind. A small pin hole should be made in filtering disc 20 to permit the passage of air from container 12 to container 14.

25 Although I have described my invention as a cap for a container in which dry cleaning fluid can be sold, it is to be pointed out that it can be sold and used as an independent unit, provided screw threads 11 and 30 13 are both adapted to fit the ordinary type of glass container known as a Mason jar. Mason jars are very widely available in pint, quart, and two quart sizes, all having the same standard screw threads. The de- 35 vice of my invention can well be made so that both screw threads 11 and 13 will fit these standard Mason jar screw threads and it can then be used by any housewife in conjunction with two Mason jars of suit- 40 able size. In any event, it will generally be desirable that screw threads 13 be adapted to fit a Mason jar, and container 14 will commonly be this type of container. Gasket 19 may suitably be the commercial ar- 45 ticle known as a Mason jar ring.

It will be understood that any of the dry cleaning fluids known to the art may be used in my device. Among these may be mentioned naphtha, carbon tetrachloride, 50 tetrachlorethylene, trichlorethylene, symmetrical tetrachlorethane, ethylene dichloride, propylene dichloride and mixtures of any of these.

Although I have described my invention 55 in connection with a specific embodiment thereof, it is obvious that various useful modifications can be made within the scope of the invention and I do not desire to be limited except by the following claims:

60 I claim:

1. An adapter to permit the use of two 65 open-mouthed containers faced mouth to mouth as a single fluid tight dry cleaning device, comprising a perforate partition, attachment means affixed to each side of said

70 perforate partition for attachment to each of said two containers and sealing means to form fluid tight joints connecting said perforate partition with each of said two containers.

75 2. A dry cleaning device comprising two open-mouthed containers faced mouth to mouth; an adapter comprising a perforate partition and attachment means affixed to each side of said perforate partition for attachment to each of said two containers; and sealing means forming fluid-tight joints between each of said containers and said adapter.

80 3. A container for dry cleaning fluid comprising an open-mouthed vessel, a perforate partition, means for attaching said partition to the mouth of said vessel, removable imperforate means disposed between said perforate partition and the mouth of said vessel to form a fluid-tight barrier over the mouth of said vessel, and means for attaching said partition to a second open-mouthed vessel disposed in a mouth to mouth position with said first mentioned vessel.

85 90 In witness whereof I have affixed my signature.
